W. A. DOREY

ILLUMINATING APPLIANCE

Filed Oct. 31, 1919

INVENTOR

William A. Dorey
BY
Joel B. Liberman
ATTORNEY

UNITED STATES PATENT OFFICE.

WILLIAM A. DOREY, OF NEWARK, OHIO, ASSIGNOR TO HOLOPHANE GLASS COMPANY, INC., OF NEW YORK, N. Y., A CORPORATION OF NEW JERSEY.

ILLUMINATING APPLIANCE.

Application filed October 31, 1919. Serial No. 334,642.

To all whom it may concern:

Be it known that I, WILLIAM A. DOREY, a citizen of the United States, and a resident of the city of Newark, county of Licking, and State of Ohio, have invented certain new and useful Improvements in Illuminating Appliances, of which the following is a specification.

The object of my invention is the construction of an illuminating appliance comprising a light transmitting globe consisting of an inner envelope resting on a lower ring member and an outer envelope supported by pressure of the inner envelope and the lower ring.

This application covers the supporting and fastening means referred to in the companion application filed this day as Serial No. 334,643 in which such means are shown in connection with one form of the device shown in the companion application, which application refers to the light directing features of the device rather than the supporting means.

25 The figure is a side elevation with parts shown in section.

In the figure, 1 is a source of light, 2 is the inner envelope of light transmitting glass. This is formed with threadings 3 at the 30 lower end adapted to thread into the cylinder ring 4 and lip 5 at the upper end adapted to hold an upper cap, 6. A base 14 supports the unit. This ring, base and cap are not necessarily of the form or size shown 35 but may have any formation as long as they are adapted for the use indicated, and hold the inner envelope positively. The outer envelope is made in two sections and is held by pressure in the manner indicated. The 40 lower outer section 7 thereof rests on a flange or rim 8 of the cylindrical ring 4. The upper rim 9 of this lower section 7 of the outer envelope permits the lower lip 10 of the upper section 11 to rest on it and by means of 45 the shape and form of lip 10 a firm seat is obtained for the two parts. The under side of lip 5 of the interior envelope presses on the upper rim of the upper section of the outer envelope. Gaskets 12 are placed between members at the various points of con-

tact to insure a firm footing. The upper cap 6 is provided with a lock-nut 13 to hold the cap firmly in contact with the upper part of the upper section of the exterior envelope.

The particular form, size and shape of prismatic enclosure is not an essential part of my invention as the feature which is claimed as novel in this application is the maintenance in firm position of the outer envelope by pressure of the parts against the interior envelope and against each other.

The metal parts of the fixture may take any form to carry out the principles of the device.

This means of attachment is particularly adapted for street lighting and kindred fields.

Having described my invention what I claim is:

1. An illuminating appliance comprising a base a ring resting thereon, an enclosing light transmitting globe and a cap therefor, the globe consisting of an inner envelope resting on the ring and supporting the cap and an outer envelope of two sections, a lower section resting on the ring and an upper section resting on the upper rim of the lower section.

2. An illuminating appliance comprising a base, a ring resting thereon, an enclosing light transmitting globe and a cap therefor, the globe consisting of an inner envelope resting on the ring and supporting the cap and an outer envelope of two sections, a lower section resting upon and supported by a flange on the ring and an upper section resting on the upper rim of the lower section.

3. An illuminating appliance comprising a base, a ring resting thereon, an enclosing light transmitting globe and a cap therefor, the globe consisting of an inner envelope with the lower part threaded on the ring and supporting the cap, and an outer envelope of two sections, a lower section resting upon and supported by a flange on the ring and an upper section resting on the upper rim of the lower section.

4. A lamp unit comprising a one piece

casing arranged at one end to fit a standard and having threads at the opposite end and an external flange between said ends, a lamp globe supported on said flange, a top resting on said globe, and a refractor extending through said top into the globe having a flange engaging said top and arranged to

screw into said casing and thereby secure the globe and top to the casing.

Signed at Newark, in the county of Licking and State of Ohio, this 28th day of October, 1919. 10

WILLIAM A. DOREY.
